HIGH SPEED MILL

William A. McLean, Geneva, N. Y., assignor to
 Geneva Processes, Inc., Geneva, N. Y., a corporation of New York

Original application January 5, 1938, Serial No. 183,549, which is a division of application Serial No. 71,932, March 31, 1936. Divided and this application June 2, 1941, Serial No. 396,336

4 Claims. (Cl. 259—8)

This invention relates to mixing devices, and more particularly to devices for mixing emulsions such as mayonnaise, salad dressings and insecticides.

The present application is a division of my copending application, Serial No. 183,549, filed January 5, 1938, now Patent 2,248,886, dated July 8, 1941, which is a division of Serial No. 71,932, filed March 31, 1936, now Patent 2,125,455, dated August 2, 1938.

An object of this invention is to provide a mixing device capable of rapidly producing a colloid or mixture of the desired homogeneity.

Another object of this invention is to provide a high speed mill which is simple in construction and which may readily be adjusted to produce a product having the desired characteristics.

Still another object of this invention is to provide a mixing device having a mixing chamber into which a rotor extends, the rotor being composed of segments of progressively increasing size.

A further object of this invention is to provide a mixing device having a mixing chamber into which a rotor extends, the rotor being provided with means which serve to give the material a beating before it leaves the mill.

With these and other objects in view, this invention embraces broadly the concept of providing a mill having a mixing chamber and a rotor extending into the chamber, the mixing chamber being provided with means to feed the material which is to be mixed in a small stream upon the center of the rotor surface.

In three forms of the invention the rotor is provided with means by which the material entering the mill is subjected to a preliminary beating before it passes between the rotor and stator surfaces. In the fourth form of the invention the material passes between one set of rotor and stator surfaces before it is subjected to the beating and then passes between a second set of rotor and stator surfaces before it leaves the mill.

The means for feeding the material into the mill is important because it enables the stator surface to be covered with the incoming material without danger of overloading the mill, and the beating of the material eliminates the necessity of thoroughly mixing the materials before they are introduced to the mill and also eliminates the possibility of the ingredients separating during the mixing process. These and other advantages will be subsequently described in more complete detail.

If desired, interlacing disturbing elements, such as interrupting circular vanes or pins such as disclosed in my co-pending application, Serial No. 396,337, filed June 2, 1941, may be used in connection with the mills disclosed in this application.

In the drawings:

Figure 1 is a view in longitudinal section of one form of the invention.

10 Figure 2 is a view taken along line 2—2 of Figure 1, looking in the direction of the arrows.

Figure 3 is a sectional view showing the rotor construction of another form of the invention.

15 Figure 4 is a sectional view showing the rotor construction of a third form of the invention.

Figure 5 is a sectional view showing the rotor construction of the fourth form of the invention.

In order to illustrate the invention, four types of mixing chambers and two types of rotors have been shown in the drawings, all of which are capable of carrying out the principal objects of the invention. All of the types of mixing chambers disclosed may be interchangeably mounted on the mill supporting structure disclosed in Figures 1 and 2.

As shown in Figure 1, the supporting structure, generally designed by the numeral 1, is provided with a base 2 which is supported by the end plate 3 of an electric motor and carries a supporting structure 4.

The mill structure 1 is also provided with an inclined surface 5 positioned intermediate a pair of side walls which combine with the inclined surface 5 to form a chute 6. The side walls 30 converge at the foot of the inclined surface 5 to form a discharge spout 7.

The front of the chute 6 is partially closed by a splash plate 8 which is held in position by knurled nuts 9 which are adapted to engage threaded studs 10 carried by the member 1. The inclined surface 5 is also provided with jacket 11 through which steam or a cooling liquid may be passed if desired.

45 The shaft 12 of the electric motor is coupled at 13 to a shaft 14 which drives a rotor member 15. The shaft 14 is journaled as indicated at 16 and 17 in a sleeve 18 which forms a part of the support structure 1 extending into the chute 6.

50 The upper portion of the support 1 defines an aperture 19 around the periphery of which a collar 20, held in position by cap screws 21, is mounted. Adjusting bolts 22, carried by brackets 55 23 which are mounted on supporting structure 1,

afford means whereby the collar 20 may be adjusted centrally with respect to the rotor shaft 14. The upper portion of the collar 20 is exteriorly threaded and is adapted to receive an interiorly threaded annulus 24 as shown at 25. The annulus 24 can be raised or lowered through rotation by means of the handles 26.

The head 27 is detachably and adjustably mounted within the collar 20 and extends into the aperture 19. The head 27 is provided with a steam or water jacket 28 which may be connected by means not shown to a suitable supply of cooling or heating fluid and which surrounds a central mixing chamber 29 of frusto-conical shape formed by walls 30. The head 27 is provided with a flange 31 which rests on the upper portion of the annulus 24 and is secured to the collar 20 by means of studs 32 provided with wing nuts 33.

The upper portion of the head 27 is provided with a centrally located aperture 34, the periphery of which is threaded to engage the exteriorly threaded extension 35 of a hopper funnel 36. The aperture 34 is of any suitable size but it is substantially smaller than the diameter of the rotor 15 and is positioned directly above the center of the rotor in order to direct the material directly upon the center of the upper surface of the rotor.

The clearance between the rotor 15 and the walls 30 of the mixing chamber 29 is regulated by raising and lowering the head 27 by changing the height of the supporting annulus 24. After the proper adjustment has been made, the wing nuts 33 are tightened to hold the head 27 in fixed position.

The rotor 15 extends into the mixing chamber 29 and consists of two frusto-conical shaped segments 37 and 38 which are mounted in superposed relation. The lower segment 37 is of larger diameter than the upper segment 38.

The construction of the rotor 15 is an important feature of the invention because it imparts an increased flexibility to the operation of the mill. In this connection it should be noted that, when the mixing chamber 29 is positioned in a manner shown in Figure 1, the upper segment 38 acts as a means to beat the emulsion entering the chamber from the funnel 36 before it passes between the working surface of the segment 37 and the walls 30. However, if it becomes advantageous because of the particular material being treated, the head 27 can be lowered in the manner previously described, thereby lowering the mixing chamber 29 and bringing the walls 30 into closer engagement with the working surfaces of both the segment 37 and the segment 38. In this position the segment 38 acts not only as a beater but as an additional agent for emulsifying the material.

Ordinarily, in actual practice after the head 27 has been adjusted so as to provide the proper clearance between the working surfaces of the rotor 15, the mixture is poured into the funnel 36 until a sufficient quantity has entered the mixing chamber 29 to completely cover the surface of the rotor. Under some conditions, if desired the entire mixing chamber 29 may be filled with the rough mixture before the mill is started. However, usually only sufficient material is admitted to cover the upper surface of the rotor segment 38.

During operation the material entering the mixing chamber through the restricted aperture 34 comes in contact with the segment 38 and is subjected to a beating and mixing action by being

thrown against the walls 30 of the mixing chamber 29. After a thorough beating and mixing, the material passes between the working surfaces of the lower segment 37 and the wall 29 and falls upon the inclined surface 5. After flowing down the surface it is discharged through the aperture 7.

In connection with the operation of the mill, it should be noted that the relatively smaller area 10 of the aperture 34 compared to the upper surface of the segment 38 of the rotor 15 permits only a restricted quantity of the material to be fed to the mill and directs all this material upon the rotor surface. The frusto-conical shape of both the rotor 15 and the mixing chamber 29 is also admirably suited for this type of mill and the adjustable feature of the head 27 allows the working surface of the mill to be increased by lowering the frusto-conical shaped mixing chamber downwardly towards the rotor 15.

In Figure 3 is shown a head 40 which may readily be substituted in the mill just described in place of the head 27. The head 40 is similar in construction to the head 27 and is provided with the previously described fluid chamber 28, flange 31 and inlet aperture 34 in which may be mounted the funnel 36 in the manner which has previously been described. The mixing chamber 41, however, is hemispherical in shape. The rotor 15 is identical in construction to that previously described and is provided with the frusto-conical segments 37 and 38.

In operation, the segment 38 acts as means to beat the material before it passes between the working space formed by the working surface 35 of the segment 37 and the walls of the mixing chamber 41.

The head 50 disclosed in Figure 4 is also provided with a fluid chamber 28, flange 31 and inlet 34. The rotor 15 is identical to that described in Figure 3, being composed of a lower segment 37 and an upper segment 38, but the extremities of the wall of the hemispherically shaped mixing chamber 51 are provided with a working surface 52 which lies in the same plane as the plane of the working surface of the frusto-conical shaped segment 37.

This type of head is desirable for use when the ingredients must be thoroughly blended and reduced to colloidal size. Due to the construction of the working surfaces, the mixture fed into the mill is subjected to an extensive beating by the segment 38 before it passes between the working surfaces.

In the form of the invention shown in Figure 5, the head 60 is provided with the previously described fluid chamber 28, flange 31 and inlet 34. The mixing chamber 61, however, is formed in two sections, the upper section 62 being frusto-conical in shape and the lower section 63 being hemispherical in shape. The rotor 64 is comprised of three segments 65, 66 and 67 which are superposed and each of which is frusto-conical in shape. These segments progressively decrease in diameter, the upper segment 67 having the smallest area.

In the position of the head 60 shown in Figure 5, the segment 67 forms a working surface with the lower portion of the upper frusto-conical chamber 62 and the lower segment 65 forms a working surface with the lower portion of the hemispherically shaped mixing chamber 63. In this position of the rotor 64, the material enters the upper mixing chamber 62 and after passing through the working surface formed by the seg-

ment 67 it is beaten and thoroughly mixed by the segment 66 by being thrown against the sides of the hemispherically shaped chamber 63. It then passes between the working surface formed by the segment 65 and the extremities of the wall of the lower chamber 63. The working surface of this mill can be decreased by slightly raising the head 60.

Therefore, the mill head 60, by being provided with a frusto-conical mixing chamber 62 and a hemispherical mixing chamber 63, has the advantages both of the mill head disclosed in Figure 2 and those disclosed in Figures 3 and 4. Moreover, the rotor in addition to being provided with two working surfaces is also provided with an intermediate beating and mixing surface.

While for purposes of illustration the preferred structure which constitutes the invention has been shown and described, it is apparent that various changes in the details of the construction can be made by those skilled in the art without departing from the spirit of the invention or exceeding the scope of the appended claims.

I claim:

1. A mixing and emulsifying mill comprising a mixing chamber having walls, the upper portion of said mixing chamber being frusto-conical in shape and the lower portion being hemispherical in shape, a rotor extending into said mixing chamber, said rotor progressively increasing in size from top to bottom and being composed of three frusto-conical shaped segments having flat upper surfaces and sloping sides, the upper of said segments forming a working surface with the walls of the frusto-conically shaped portion of the mixing chamber and the sloping surface of the lower segment forming a working surface with the walls of the hemispherically shaped portion of the mixing chamber, and said intermediate segment being spaced from the walls of the hemispherically shaped portion of the mixing chamber to serve as a beater.

2. A mixing and emulsifying mill comprising a mixing chamber having walls, the upper portion of said mixing chamber being frusto-conical in shape and the lower portion being hemispherical in shape, a rotor extending into said mixing chamber, said rotor progressively increasing in size from top to bottom and being composed of three frusto-conical shaped segments having flat upper surfaces and sloping sides, the upper of said segments forming a working surface with the walls of the frusto-conically shaped portion of the mixing chamber and the sloping surface of the lower segment forming a working surface with the walls of the hemispherically shaped portion of the mixing chamber to serve as a beater.

portion of the mixing chamber, and said intermediate segment being spaced from the walls of the hemispherically shaped portion of the mixing chamber to serve as a beater, and the upper portion of said mixing chamber defining an opening of restricted area positioned above the center portion of the said rotor.

3. A mixing and emulsifying mill comprising a mixing chamber having walls, the upper portion of said mixing chamber being frusto-conical in shape and the lower portion being hemispherical in shape, a rotor extending into said mixing chamber, said rotor progressively increasing in size from top to bottom and being composed of three frusto-conical shaped segments having flat upper surfaces and sloping sides, the sloping surface of the upper of said segments forming a working surface with the walls of the frusto-conically shaped portion of the mixing chamber and the sloping surface of the lower segment forming a working surface with the walls of the hemispherically shaped portion of the mixing chamber, and said intermediate segment being spaced from the said hemispherical shaped portion of the mixing chamber to serve as a beater, the upper portion of said mixing chamber defining an opening of restricted area positioned above the center portion of the said rotor, and the said mixing chamber being adjustable vertically so that the distance of the upper surface of the rotor from the said opening may be regulated.

4. A mixing and emulsifying mill comprising a mixing chamber having walls, the upper portion of said mixing chamber being frusto-conical in shape and the lower portion being hemispherical in shape, a rotor extending into said mixing chamber, said rotor progressively increasing in size from top to bottom and being composed of at least three frusto-conical shaped segments having flat upper surfaces and sloping sides, the sloping surface of the upper of said segments forming a working surface with the walls of the frusto-conically shaped portion of the mixing chamber and the sloping surface of the lower segment forming a working surface with the walls of the hemispherically shaped portion of the mixing chamber, and said intermediate segments being spaced from the said hemispherical shaped portion of the mixing chamber to serve as a beater, the upper portion of said mixing chamber defining an opening of restricted area positioned above the center portion of the said rotor, and the said mixing chamber being adjustable vertically so that the distance of the upper surface of the rotor from the said opening may be regulated.

WILLIAM A. MCLEAN.
